UNITED STATES PATENT OFFICE.

ANDREW McLAIN, OF CARNEGIE, PENNSYLVANIA.

SPIKE PULLER.

Application filed March 10, 1923. Serial No. 624,165.

To all whom it may concern:

Be it known that I, ANDREW McLAIN, a citizen of the United States and resident of Carnegie, in the county of Allegheny and State of Pennsylvania, have invented a new and useful Improvement in Spike Pullers; and I do hereby declare the following to be a full, clear, and exact description thereof.

My invention relates to spike pullers, and is specially designed for heavy service such as the pulling of railway spikes from ties.

The object of my invention is to provide an improved spike puller which shall be simple in construction, convenient in operation and capable of exerting a powerful lifting force which operates to draw the spike in a vertical direction from the tie.

Another object of my invention is to provide a spike puller of the character indicated which shall be able to engage the head of the spike or nail in cases where there is but little clearance between the head and the tie or other object in which the spike is embedded.

In the accompanying drawing, Fig. 1 is a side elevational view of the lower end of a spike puller constructed in accordance with my invention, the spike puller being shown in the course of being applied to a railway spike; Fig. 2 is a similar view, with parts in section, showing in full lines the position of the spike puller when it is in proper position to begin raising the spike, and showing in dotted lines another position of the spike puller while it is raising the spike; and Fig. 3 is a rear elevational view of the same spike puller in the full-line position of Fig. 2.

In the drawing, the numeral 2 indicates the shank of a claw bar having a bifurcated claw 3 formed at its lower end and also having a circularly curved enlargement 4 back of the claw, the curved surface 5 of this enlargement being circular around a central point 6.

The circularly curved surface 5 merges into a flat under surface 7, which connects the curved surface 5 with the pointed end of the claw. At the point 6 and opening is formed from side to side through the bar and receives a bolt 8. This bolt supports two links 9 which are provided with slots 10 surrounding the bolt 8, as best shown on Fig. 2. The lower ends of the links 9 are connected pivotally to a wedge-shape fulcrum member 11 provided with serrations

on its under surface, as shown at 12. The connection between the links 9 and the fulcrum member 11 is made by means of screw bolts 13 which extend through openings near the lower ends of the links 9 and into corresponding tapped openings in the sides of the fulcrum member 11.

As shown on the drawing, the spike puller is provided with an adjustable grab hook, the construction of which is described and claimed in Letters Patent No. 1,326,758, granted to me December 30, 1919. This grab hook, as shown, comprises a fork having two arms 15 provided near their ends with openings to receive the bolt 8 and connected to a straight arm 16 which carries a sliding member 17. The member 17 may be secured in any desired position on the arm 16 by means of a wedge member 18 which extends through the same opening in the member 17 which admits the arm 16. This grab hook construction forms no part of my present invention, and the grab hook may be entirely omitted if desired.

It will be noted particularly that the claw 3 is connected to the curved working surface 5 of the claw bar by means of the straight surface 7, and that the claw 3 is not curved upwardly, as is usual in claw bars of this kind. This construction enables the claw to be thrust beneath the head of the spike, and enables the fulcrum member to be properly adjusted without rocking the bar forward much beyond its vertical position, even though the head of the spike may be driven nearly flush with the upper surface of the tie.

It will also be noted particularly that the upper surface of the wedge-shaped fulcrum member 11 is straight, thus enabling the curved surface 5 to roll without sliding friction upon the upper surface of the fulcrum member when the bar is rocked in the operation of pulling a spike. It will be noted further that the slotted connection between the links 9 and the pivoted bolt 8 cause the fulcrum member to act independently of the pivot bolt while a spike is being pulled. Therefore, the load is supported wholly by the fulcrum member and not by the pivot bolt, which is an advantage because the pressure developed in a spike puller of this kind is so great that the pivot bolt might be sheared off if the load were supported on that bolt.

Fig. 1 shows the manner in which the

spike puller is first brought into engagement with a spike A, which is shown embedded in a tie B adjacent to a rail C. The claw 3 is first placed astride of the spike, 5 as shown in Fig. 1, the grab hook if used being raised so as to pass over the top of the rail C. The handle of the claw bar is then rocked forward into the position shown in full lines on Fig. 2. The bar rocks on the 10 point of its claw 3, and the fulcrum member 11 falls by its own weight into the position shown in Fig. 2, where its flat upper surface rests against the flat under surface 11 of the claw bar. At the same time the 15 grab hook, if used, falls beyond the rail into the position shown in Fig. 2.

The claw bar 2 is then rocked away from the tie. This immediately causes the circularly curved surface 5 of the claw bar to 20 roll upon the flat upper surface of the fulcrum member 11, and the claw 3 raises the spike A in a vertical direction. Fig. 2 shows in dotted lines the position of the parts during this drawing operation.

25 While the construction shown and described herein has been found to be effective in actual use, it will be understood that various changes in the construction and arrangement of parts may be made without 30 departing from my invention, the scope of which is indicated in the appended claims.

I claim as my invention:

1. A spike puller comprising a claw bar having a claw and a curved working surface 35 behind said claw, and a forwardly tapered fulcrum member pivotally secured to said bar and having a flat upper surface arranged to cooperate with the said curved working surface of said claw bar.
2. A spike puller comprising a claw bar 40 having a claw, a curved working surface

behind said claw and connected with said claw by a straight under surface, a fulcrum member having a flat upper surface adapted to cooperate with said curved working surface, links pivotally connected to said fulcrum member, and slotted connections between said links and said claw bar. 45

3. A spike puller comprising a claw bar having a claw, a curved working surface 50 behind said claw and connected with said claw by a straight under surface, a wedge-shaped fulcrum member having a flat upper surface adapted to cooperate with said curved working surface, a pivot member extending through an opening in said claw bar, and links pivotally connected to said fulcrum member, said links having slots 55 through which said pivot member extends.

4. A spike puller comprising a claw bar having a claw, a straight under surface adjacent to said claw, a projection in the rear of said straight under surface, the said projection having a working surface that is circularly curved about a point within said claw bar, a pivot member extending through an opening substantially at the said center of curvature, links having longitudinal slots through which said pivot member extends, a wedge-shaped fulcrum member 70 suspended pivotally from the outer ends of said links, the said fulcrum member having a flat upper surface adapted to engage the flat under surface of said claw bar when the said claw is applied to a spike, and being also adapted to cooperate with said curved working surface to cause said claw to lift the spike, and serrations formed on the under surface of said fulcrum member. 75

In testimony whereof I the said ANDREW 80 McLAIN have hereunto set my hand.
ANDREW McLAIN.
